UNITED STATES PATENT OFFICE.

GEORGE E. BEANE, OF WHITE STONE, VIRGINIA.

WASHING-MACHINE.

SPECIFICATION forming part of Letters Patent No. 398,486, dated February 26, 1889.

Application filed July 14, 1888. Serial No. 279,910. (Model.)

To all whom it may concern:

Be it known that I, GEORGE E. BEANE, a citizen of the United States, residing at White Stone, in the county of Lancaster and State of Virginia, have invented certain new and useful Improvements in Washing-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The invention relates to that class of washing-machines wherein the clothes are held and rubbed up and down over a stationary wash-board.

The invention will first be described in connection with the drawings, and then pointed out in the claim.

Figure 1 of the drawings is a longitudinal vertical section on the dotted line $x x$ of Fig. 2, and Fig. 2 is a vertical cross-section on dotted line $y y$ of Fig. 1.

In the drawings, A represents the suds-box, provided at the bottom with legs a , at the top with handles a' , with a soap-box, a^2 , a wringer, a^3 , and a receptacle, a^4 , for the clothes after 30 they have passed through the wringer. In the longitudinal middle of the suds-box A, I make fast the vertical wash-board B, corrugated on both sides, but preferably not extending to the bottom of the suds-box. From this project vertical standards $b b$, with the perforations b' , through which pass the fulcrum-rod C of the lever-frame D, which may thus be fulcrumed at different altitudes. At an equal distance from the fulcrum C pass the 35 pivot-rods $c c$, on which are pivoted the bars E E, which carry at their lower ends the followers F F. The rods c have holes c' , so that the bars and lever-frame may always be correspondingly adjusted. The followers F 40 are fixed to the bars E on a downward incline from the wash-board B toward the side of the

suds-box, so as to press the clothes on the wash-board B.

G G are perforated boards, on which the clothes rest, and are provided with arms g , suspended by springs g' from a horizontal rod, H, the latter being supported on the box-standards I I.

The operation is as follows: I place the clothes on the spring-boards G, adjust the 55 lever frame and followers correspondingly to suit the quantity of clothing on the boards G, and pour hot suds into the box A until they reach to or nearly to the top of the wash-board B. The clothes are now grasped between the 60 followers F and spring-boards G, and as the lever-frame is vibrated are rubbed up and down against the wash-board. By removing the fulcrum C and withdrawing the followers the position of the clothes may be changed and 65 the clothes again rubbed, this being continued until the dirt has been completely eliminated from the garments, which are then passed through the wringer and dropped into the receptacle a^4 .

This machine has been practically tested by me and been found to do its work with singular efficiency and with great rapidity.

What I claim as new, and desire to protect by Letters Patent, is—

The wash-board B, fixed in the middle of the suds-box A, but not extending to the bottom thereof, and provided with vertical standards $b b$, perforated at b' , in combination with two inclined followers, F F, having standards E E, 80 perforated at c' , and two clothes-rests, G G, arranged on the lower ends of arms g , suspended from springs g' , whereby said parts are adapted to be used in connection with an adjustable lever-frame, C D, in the manner 85 described.

In testimony whereof I affix my signature in presence of two witnesses.

GEORGE E. BEANE.

Witnesses:

A. RUPPERT,
PHILIP MAURO.
